An ornamental design for a padded men's shirt, as shown and described.

DESCRIPTION

FIG. 1 is a front elevational view of the padded men's shirt not being worn and showing the outer surface of the front portion of the garment, the black lines in a thickness of 2pts show the internal padding placement and its formed outline; FIG. 2 is a back elevational view of the padded men's shirt of FIG. 1;

FIG. 3 is a left plan view thereof;

FIG. 4 is a right plan view thereof;

FIG. 5 is a top plan view thereof;

FIG. 7 is a front elevational view of the padded men's shirt not being worn and the shirt is in an inside-out configuration, showing an inside of the garment, dashed dotted lines showing stitches;

FIG. 8 is a left plan view of the padded men's shirt of FIG. 7 and the right plan view is a mirror image of the left plan view;

FIG. 9 is a back elevational view of the padded men's shirt of FIG. 7;

FIG. 10 is a front plan view of the padded men's shirt of FIG. 1, wherein the shirt is in a worn configuration thus creating the appearance of less-pronounced outer edges of each chest pad represented with lighter grey lines at a thickness of 0.25 pts;

FIG. 11 is a left side perspective view of the padded men's shirt in FIG. 10; and,

FIG. 12 is a right side perspective view of the padded men's shirt in FIG. 10.

The dashed dotted lines on the design indicate stitching. The broken lines showing the remainder of the garment illustrate the environment in which the design is used. None of the broken-line subject matter forms a part of the claimed design. The surface outside or adjacent to the solid line form no part of the claimed design.
